DESIGN FOR A SLIPPER

Louis E. Friedman, Brooklyn, N. Y.

Application December 8, 1939, Serial No. 88,773

Term of patent 3½ years

To all whom it may concern:

Be it known that I, Louis E. Friedman, a citizen of the United States of America, residing in Brooklyn, county of Kings, and State of New York, have invented a new, original, and ornamental Design for a Slipper, of which the following is a specification, reference being had to the accompanying drawing, forming part thereof.

Fig. 1 is a plan view of a slipper showing my new design.

Fig. 2 is a side elevational view thereof.

I claim:

The ornamental design for a slipper, substantially as shown.

LOUIS E. FRIEDMAN,
